UNITED STATES PATENT OFFICE.

LOUIS B. PRAHAR, OF BROOKLYN, NEW YORK.

DESIGN FOR A BELT-BUCKLE.

SPECIFICATION forming part of Design No. 35,957, dated June 17, 1902.

Application filed May 18, 1902. Serial No. 107,209. Term of patent 7 years.

To all whom it may concern:

Be it known that I, LOUIS B. PRAHAR, a citizen of the United States, and a resident of the city of New York, borough of Brooklyn, in the county of Kings and State of New York, have invented and produced a new and original Design for a Belt-Buckle, of which the following is a specification, reference being had to the accompanying drawing, forming a part thereof, in which is shown a front elevation of a buckle embodying the features of my design.

The buckle presents a shield-like outline, and at each side of the center of the buckle the representation of a flower of the daisy type is produced, the leaves appearing with

clear spaces between them, and the space between the margin of the buckle and the marginal portion of the floral figures appears in bead effect.

Having thus described my invention, I claim as new and desire to secure by Letters Patent—

The design for a belt-buckle herein shown and described.

In testimony whereof I have signed my name to this specification in the presence of two subscribing witnesses.

LOUIS B. PRAHAR.
